F. E. Maynard, ATTORNEYS.

UNITED STATES PATENT OFFICE.

JOY V. WENTWORTH, OF LONG BEACH, CALIFORNIA, ASSIGNOR OF ONE-HALF TO
JOHN JOSEPH LONG, OF LONG BEACH, CALIFORNIA.

SPOOL PULLER.

Application filed May 9, 1928. Serial No. 276,286.

This invention relates to heavy duty tools for use in oil fields and other places where it is desirable to pull spool drums sometimes called "cat heads" from their shafts.

5 It is an object to provide a simple and powerful tool of easy application and removal, and of few parts which are designed for safety of operation and reliable action.

Other objects, advantages and details of 10 construction and combination will be made manifest in the ensuing description of the herewith illustrative embodiment; it being understood that modifications, variations and adaptations may be resorted to within the 15 spirit, scope and principle of the invention as it is hereinafter more directly claimed.

Figure 1 is a side elevation of the applied tool.

Figure 2 is a clamp-end view of the tool. 20 Figure 3 is a detail showing the jack screw as having a ball-bearing point.

The tool is here shown as applied to a "cat-head" spool C on a shaft S. Spools of this type are large and heavy and have round- 25 ed bead flanges F.

The present device includes a strong C- 30 clamp frame 2 having a central boss 3 threaded for a jack screw 4 having a cone point for centering on the shaft end. The hook ends 3' of the clamp reach in over the spool flange and to the ends 3' are applied opposed semi-circular collar parts 6—7 whose diameter is such as to embrace the body of the spool and pull up behind the outer flange F.

35 The split collar has ears 8 clamped to the frame hooks by means of bolts 9.

When the tool is to be used the screw 4 is run back and the clamp frame 2 is set across the end of the spool and shaft, the collar parts are now applied around the spool and the bolts 9 run in and set to secure the ring 6—7 in place. The screw 4 is now turned in

against the shaft S and the spool C is pulled loose or off the shaft.

It is understood that the tool may be applied to many kinds of winding drums and other machines and parts. 45

It will be seen that the pressure of pulling is taken all around the cat head flange and evenly distributed so as not to bind the drum 50 on its shaft.

Figure 3 illustrates the jack screw 4 as having a turnhead 4' and an interposed ball-bearing 4^a whereby to reduce back pressure 55 on the screw during action.

What is claimed is:

1. A "cat head" drum puller including a C-clamp frame whose hook ends are applicable to catch behind the flange on the end of the mounted drum, a center screw in the 60 frame for action against the drum shaft, and a pair of half rings applicable to the drum and behind its flange, and means for securing the half rings in collar forming position about the drum and fastening them 65 to the respective side faces of the hook-ends of the frame.

2. A drum puller having a C-clamp frame having pulling hooks to catch a "cat head" flange, a center jack-screw therefor, and a 70 collar consisting of semicircular parts having ears to seat on opposite sides of the clamp hooks, and bolts securing the applied ears in place.

3. A "cat head" drum puller including a 75 C-clamp with hook ends to over-reach the contiguous end bead of the drum, and a jack screw passing through the medial body portion of the clamp and having a rotative thrust end, and a ball-bearing interposed between 80 the thrust end and the contiguous part of the screw.

JOY V. WENTWORTH.
